UNITED STATES PATENT OFFICE.

WARREN F. FARAGHER AND WILLIAM ARTHUR GRUSE, OF PITTSBURGH, PENNSYLVANIA, ASSIGNEES TO GULF REFINING COMPANY, OF PITTSBURGH, PENNSYLVANIA, A CORPORATION OF TEXAS.

PROCESS AND APPARATUS FOR CRACKING HYDROCARBON OILS.

Application filed January 15, 1921. Serial No. 437,479.

This invention relates to an improved method and apparatus for making motor fuel or gasoline by cracking hydro-carbon oils, such as the higher boiling fractions and residual oils of petroleum or shale oil distillation.

When hydrocarbon oils of the character referred to are subjected to cracking in an externally heated still, serious difficulties are encountered in large-scale operations, due to the deposition of a carbonaceous solid, commonly referred to as "carbon," on the heated walls of the still. Such a deposition of "carbon" interferes with the conduction of heat into the oil, and results in increased cost of gasoline-production owing to the necessity of cleaning the "carbon" from the still-walls and the loss of operating time during such cleaning operations; while the life of the still-wall is comparatively short due to the rapid burning out of the iron in contact with "carbon."

Attempts have been made to overcome the difficulties mentioned by providing stirrers in the still for agitating the oil, but such stirrers are open to the objection that they require stuffing boxes which must operate against highly heated oil or heated oil vapors at high pressures.

According to the present invention, the difficulties above referred to are overcome or minimized, and an efficient circulation of the oil through the heated portion of the still is effected, with avoidance or substantial avoidance of objectionable deposition of carbon on the still-walls, by providing an upright tubular still, or the upright tubular portion of a still, with a suitable eduction-pipe or tube, and by so introducing a gaseous current or currents, acting on the "air-lift" principle, that effective circulation of the oil through the heated portion of the still takes place, and the formation of a "dead layer" of oil on the hot walls of the still is avoided.

The gas used in the stirring and circulation of the oil, according to the present invention, may with advantage be the fixed gas formed during the cracking-operation, but other appropriate gas can be used, such as natural gas or casing-head gas, steam, etc. which has no objectionable effect upon the cracking operation.

In the preferred practice of the invention, only a portion of the still is heated and the oil is circulated continuously through this heated portion of the still by the provision therein of a suitable eduction-pipe and the introduction of a current or currents of gas acting, in conjunction with the eduction-pipe, on the "air-lift" principle. The still may itself be a tubular still, vertical or inclined, having the eduction-pipe vertically arranged therein, or, if inclined, having a sufficient vertical component to provide for the circulation desired; or the still may be of the boiler type provided with vertical legs extending into the furnace and each having an "air-lift" circulating device, so that the boiler will act as a reservoir for the oil which is heated to the cracking-temperature by continuous circulation of a part thereof through the depending legs. The gas may be introduced within the eduction-pipe so that it will draw in oil at the bottom and discharge it from the top and so that the oil will then flow down continuously outside the eduction-pipe and be again recirculated; or the gas can be introduced in the space between the eduction-pipe and the still to cause a rapid upward current of oil in this space with the downward return of oil through the inside of the pipe.

The introduction of a current or currents of gas not only serves to insure effective agitation and circulation of the oil, but it promotes the regular removal of the lower-boiling constituents resulting from the cracking operation as they are formed, and prevents their remaining in the still to undergo further decomposition. The excess gas, resulting from the cracking operation, can be discharged from the still in any of the usual ways, while the gas that is to be recirculated through the still can be freed from undesired high boiling constituents in a suitable dephlegmator, and from the desired condensable constituents in a suitable condenser, and can then be passed through a pump or gas-booster and sufficiently increased in pressure to be used again.

In the practice of the process, the oil is continuously circulated through the heated portion of the still in such a way that its temperature is raised into that range in which cracking occurs with the production

of considerable naphtha and gasoline and relatively little gas and "carbon," without local overheating of any portion of the oil to the still higher temperatures at which much 5 gas and "carbon" are formed. The continuous and effective circulation of the oil in the heated portion of the still keeps the oil within the desired temperature range throughout and gives a resulting uniform cracking 10 operation, while avoiding local overheating. The oil which becomes heated by its circulation into contact with the heated walls of the still is continuously swept or scoured off so that the formation of a "dead layer" of 15 oil is prevented, with resulting prevention of the heating of such a layer to objectionably high temperatures.

The apparatus embodying the invention, in which the improved process of the invention 20 can be practiced, may have a great variety of forms, and may be operated either continuously or discontinuously. A single still may thus be provided adapted to operate upon successive charges of oil, or to 25 operate in a continuous manner by the continuous introduction of oil and the continuous or periodical removal of residue; or a series of stills can be arranged to act successively upon a body of oil which is caused 30 to pass through them under properly regulated conditions of temperature and pressure. The still may with advantage be provided with a "tar pot" below the furnace and circulating portion of the still, for the 35 collection of "carbon" and insoluble substances.

The utilization of the "air-lift" mechanism and principle for effecting circulation makes possible efficient circulation of the oil 40 without the use of moving mechanism and therefore without the use of stuffing boxes, so that all connections of the still may be welded and made gas tight. The gas is also used to much better advantage than is the 45 case when it is allowed merely to bubble through a charge of oil in the still, since the use of the gas in accordance with the air-lift principle and mechanism insures a positive 50 flow of oil along the still walls with a sufficient velocity to break up the dead layer of oil which has heretofore been the chief cause of "carbon" trouble and deposit.

The invention will be further illustrated 55 and described in connection with the accompanying drawings which show, in a somewhat conventional and diagrammatic manner, different forms of apparatus embodying the invention and adapted for the practice of the process of the invention.

60 In the accompanying drawings:

Fig. 1 shows one form of apparatus with the gas introduction pipe arranged within the eduction-pipe;

Fig. 2 shows a modified construction with 65 arrangement for introducing the gas into

the annular space between the central tube and the still wall;

Fig. 3 is a sectional view taken on the line 3—3 of Fig. 2;

Fig. 4 shows a modified construction in 70 which a boiler type still is provided with several depending legs each provided with circulating means;

Fig. 5 is a vertical transverse section of the apparatus of Fig. 4;

Fig. 6 shows a modified construction in 75 which a series of stills are provided; and

Fig. 7 shows, somewhat diagrammatically, the assembly of a single tube still with condenser, preheaters, etc.

In the different figures of the drawing, similar parts are referred to by the same numerals, with different letters appended thereto.

In the apparatus of Fig. 1 the still 1 is 80 a vertical tubular still having an oil inlet pipe 2, dephlegmating column 3 with vapor pipe 4 leading therefrom to the condenser, and with a settling chamber or tar pot 5 at the bottom from which the residue can be 85 withdrawn through the outlet 6. A suitable furnace chamber 7, heated by direct heat or by products of combustion, surrounds a part of the still, so that only a portion of the still is heated. Within the 90 heated portion of the still is arranged an eduction tube 8, suitably supported by supports 12, and a gas inlet pipe 9 is arranged with its foot-piece 11 so that it discharges the gaseous current upwardly within a 95 restricted portion of the eduction tube 8, as shown. The gaseous current can be controlled by means of a suitable regulating valve 10.

In the operation of the apparatus of 100 Fig. 1 the gas, which may be the fixed gas from the cracking operation, is forced into the pipe 9 and discharged upwardly through the foot-piece 11 into the central eduction pipe 8, thereby drawing in oil at the bottom 105 of the eduction pipe and causing upward circulation therethrough. This oil is discharged at the top of the eduction tube, together with the gas, and the oil flows down continuously between the eduction tube and still wall to be again recirculated. A continuous circulation of the oil is thus effected, with resulting uniformity of temperature of the oil body as a whole and resulting avoidance of objectionable overheating of the oil 110 next to the still wall. The entire body of oil can thus be brought within the range of temperatures most favorable to cracking and maintained within such range without local overheating. The gas introduced into the 115 still through the gas inlet pipe escapes, together with the gaseous products of cracking and of distillation, through the dephlegmator 3, where undesired high-boiling constituents are condensed and returned to the 120

125 130

still, and then through the condenser (not shown) where condensable constituents are separated. If the condenser is operated under the same pressure as the still, the fixed gas can be withdrawn at this pressure and recirculated, so that no considerable further compression is necessary. Instead of first passing the gas through the condenser and thereby cooling it, the hot gas may be taken off at some point between the final condenser and the still at a correspondingly elevated temperature, and can be recirculated so that its sensible heat is in large part conserved.

In the apparatus of Figs. 2 and 3, the gas is introduced or liberated into the annular space between the still walls 1^a and the central tube 8^a, so that the oil is caused to flow upwardly through the heated annular zone around the central tube and then downwardly through the central tube. The diameter of the central pipe is increased in this case so that the velocity of the oil through this annular space is very considerably increased. It is of course obvious that in whatever form used, the eduction tube must be of such size and so placed with reference to the heated still wall as to give a vigorous circulation of oil along and against the heated still wall.

In the apparatus of Figs. 4 and 5 the still 14 is a boiler type still having three depending legs 1^b, each exposed to the furnace for a portion of its length, and each provided with a circulating device similar to that of Fig. 1 or Fig. 2. The boiler 14 in this case acts as a reservoir for the oil which is heated to the cracking temperature range by continuous circulation of a portion of the oil through the depending legs, each of which is provided with an air-lift circulating device. The boiler 14 is provided with a separate outlet 15 for the residue, in addition to the outlets 6^b at the bottom of the depending legs. The lower part of the boiler is also surrounded by a flue construction 17 (shown only in Fig. 3) by means of which it is heated by the waste gases from the furnace 7^b, the boiler portion of the apparatus thus acting as a reservoir in which entering oil is preheated.

In the apparatus of Fig. 6 a series of four tubular stills 1^c, 1^d, 1^e and 1^f, is arranged so that the oil can be introduced into the first still and passed through each of the others in succession. The oil may thus be introduced into the still 1^c, through the inlet pipe 2^c, and the oil from this still then passed into the still 1^d, and so on. Connecting pipes 18, 19 and 20 are arranged between the stills and provided with both hand operated and adjustable automatically operating regulating valves. The flow from one still to the next may be by gravity, in which case the hand operated valves are opened and the pumps are not employed, or the pumps 21,

22 and 23 may be used so that the oil can be pumped from one still into the next. The four stills, in this case, may have separate and separately controlled outlet pipes which may lead to a common vapor line 19 and 70 a common condenser. In such case, the outlet pipes 4^d, 4^e, 4^f and 4^g are provided with suitable regulating valves, such as the automatic adjustable relief valves 40^d, 40^e, 40^f and 40^g, so that the different unit stills 75 may operate at different temperatures and pressures. It is to be understood that the temperatures and pressure may be regulated independently in each still. The "bottoms" may be withdrawn continuously from the 80 last still of the series, or from any one of the series, as the character of the oil treated and the conditions of operation may require.

In Fig. 7 there is represented diagrammatically the assembly of a single tube still of a construction such as is shown in Fig. 2, with appropriate condenser, preheaters, heat exchangers, pumps, etc. The condenser is illustrated conventionally at 25 and the receiver for the condensate at 26, this receiver having an outlet pipe 27 with an automatic relief valve 28 therein, and also having an outlet pipe 29 for the fixed gases leading to the vapor pipe 30 which supplies the gas blower 31 with the gas or vapor introduced into the still through the pipe 32 and the gas or vapor inlet pipe 9^a. The vapor pipe 30 is also connected with the main vapor pipe 4^a, so that the gases introduced into the still may be either the fixed 100 gases from the receiver 26, or admixed gases and vapors obtained through the pipe 30, or a mixture of both in varying proportions.

A constant level can be maintained in the still in any suitable manner, for example, by feeding the oil to the still, in the apparatus of Fig. 7, through the pipe 35, from the oil supply vessel 34 in which a constant level is maintained by any suitable means (not shown). The oil to be supplied to the still enters through the pipe 36 and is pumped by the pump 37 through the preheater 39, where it is preheated by the residue from the bottom of the still, then through the preheater 40 where it is further preheated in any suitable manner, and it enters the constant level supply vessel 34 in a preheated condition and is supplied in this condition to the still. The operation of the pump 37 is automatically controlled (by means not shown) so that it will maintain a constant level in the supply vessel 34 which, in turn, supplies the still and maintains a constant level therein. The supply vessel 34 is connected with the vapor pipe 30 by branch pipe 33 so that the same pressure is maintained in the supply vessel as in the still.

In the operation of the apparatus shown 130 in the various figures, and the practice of the

- improved oil cracking process therein, the oil is maintained at a suitable level, for example, at the level indicated at 16 in Fig. 1 or 16^b in Fig. 5 or 42 in Fig. 7, and this level can be automatically maintained by the introduction of further amounts of oil through a suitably regulated oil supply pipe. The residuum can be drawn off through the bottom outlet of the still either continuously or intermittently, and its heat utilized in the preheater 39 of Fig. 7 for assisting in preheating the oil supplied to the still. The gaseous and vapor products resulting from the cracking and distilling operation together with the gas introduced through the gas inlet pipe or pipes, are taken off through the dephlegmator and vapor pipe to the condenser 25 of Fig. 7, or other suitable condenser. If the condenser is to be operated under the same pressure as the still, which is the preferred practice, the regulating valve may be beyond the condenser, as indicated at 28 in Fig. 7, and the pipe leading from the still will then require no regulating valve. If the condenser is to be operated under a lower pressure than the still, suitable regulating valves (not shown) can be provided in the vapor pipe 4^a leading from the still to the condenser and in line 29. The necessary gas for recirculation can be withdrawn either at the still pressure and temperature and reintroduced into the still, or the gas can be used after it has passed through the condenser and been freed from condensable constituents. The diagrammatic arrangement of Fig. 7 provides either for using the hot compressed gases from the still and recirculating them, or for recirculating the fixed gases after the condensable constituents have been removed. This arrangement for making use of the gases, or gases and vapors, produced by the process, is a particularly advantageous method of procedure. Other suitable gas than that resulting from the cracking operation can, however, be used in the practice of the invention, as well as other gaseous materials such as steam, although it will usually be more advantageous to make use of the gas or vapors produced by the cracking operation and to return and reuse such gases repeatedly. By drawing off the hot compressed gases or vapors from the still, they can be used with conservation of their temperature and pressure, so that only a small increase in pressure is required for recirculation, and so that the recirculated gas does not exert any considerable cooling action on the oil. The oil feed to the still may be preheated to a greater or less extent, as above noted. A part of the necessary heat can be supplied by means of a heat interchanger 39 through which the still "bottoms" are discharged; while a part of the preheating may be

effected by bringing the oil feed into heat interchanging relation with the hot vapors from the still. The oil feed can thus be passed through the condenser for the vapors from the still, or through one or more of the 70 series of such condensers, where such a series is used for fractionally cooling and condensing such vapors. The preheating effect thus secured may be supplemented, if desired, by further preheating of the oil feed 75 in any suitable manner, and the oil feed can advantageously be preheated to such a degree as to vaporize and remove any water present therein.

In illustrating the various forms of apparatus in the accompanying drawings, we have omitted the heat insulation or lagging of the still, connecting pipes, etc., but it will be understood that, in practice, suitable heat insulation will be provided to avoid objectionable losses from all exposed parts of the still and of the system which become heated.

It will be understood that the stills of Figs. 1 to 6 are provided with suitable pressure, temperature and level indicating devices (not shown) as well as with means for producing and maintaining within the still the necessary temperature and pressure conditions for the cracking operation. The cracking operation may thus be carried out 95 under a regulated pressure, for example, of between 60 and 500 pounds per square inch, and preferably in the neighborhood of 75 to 150 pounds per square inch, depending upon the nature of the oil to be cracked and the 100 products desired. The continuous rapid circulation of the oil through the heated zone of the still promotes the uniformity of heating and enables substantially all the entire body of oil to be maintained at the desired 105 temperature for most effective cracking of the particular oil treated.

In the practice of the invention, the rapid circulation of the oil with respect to the heated iron surfaces of the tubular still will 110 effectively prevent the formation of objectionable carbon deposits and tend to remove any carbon that may incidentally be formed. Such carbon as is formed in the circulating oil will promote the erosive action of the oil 115 and tend to scour off any carbon deposit. This erosive action can be further increased by adding a little sand, fine gravel, or metal filings to the oil which is thus rapidly circulated over the heated iron surfaces.

Owing to the rapid motion of the oil and the resulting uniform temperature and avoidance of local overheating, the resulting cracking operation is of a more uniform character and results in a higher yield of gasoline and lower gas and coke losses, and hence an increased capacity or improved yields for a given sized still, while the effective life of the still is at the same time increased, and the still can be run for long periods of time 130

without the necessity for discontinuing operations for cleaning purposes. The provision of a tubular form of still, with continuous operation, avoids the danger of having a 5 large volume of highly heated oil under pressure subjected to further heating effect, as in the usual boiler type stills heated by direct heat. So also, the keeping of the still walls of the heated zone free or substantially 10 free from carbon deposit and from a layer of dead oil permits the use of a greater heat influx to the oil and consequently a greater capacity for a still of definite size.

It will thus be seen that the improved 15 process and apparatus of the present invention enable the cracking of oils and the production of motor fuel or naphtha to be effected in an advantageous manner, with increased efficiency and uniformity of operation, and with substantial avoidance of the 20 usual difficulties met with in cracking processes, due to carbon deposition; and that the improved results are obtained in a simple and advantageous manner.

25 In referring to the cracking of "oil" in the present specification and claims, we intend to include the treatment of various hydrocarbon oils, and more particularly the treatment of higher boiling fractions and residual 30 oils of petroleum or shale oil distillation, for the production of motor fuel or gasolene; but other oils, such as lignite or coal tar, or tar oils, etc., can be similarly treated; and we include all such materials within the term 35 "oil", as used in the accompanying claims.

It will, of course, be understood that the 40 passages governing the circulation in the still are not restricted to any particular shape or location, provided only that they serve as a means for constantly sweeping away the "dead oil" from the highly heated cracking surfaces. They may have, therefore, any shape or disposition that will effect that purpose.

45 In referring to the "air-lift principle" herein we refer to the same principle that is applied in pumping water where air is pumped into and mixed with water in one of two balanced columns so that flow is set 50 up due to the reduction of density in the column into which the air is introduced. In the present application of this principle flow is caused by the reduction of density of the oil body into which the gas streams are 55 introduced and the kinetic energy of injected gas streams is not relied upon for maintaining the circulation. In carrying out the 60 process and in the operation of the apparatus of the present invention, circulation is effected without reference to the velocity of introduction of the gas streams and the sim-

ple liberation of the gas in the oil at zero velocity is sufficient to maintain circulation in accordance with the present invention.

We claim:

1. The method of cracking oils, which comprises subjecting a body of oil in a still to the action of heated surfaces and thereby heating the oil to a cracking temperature under pressure and introducing a current or 70 currents of gas, acting on the "air-lift" principle, in upwardly directed jets in an upwardly directed passage within the body of oil, the gaseous current or currents being made up of gases produced during the crack- 75 ing operation.

2. The method of cracking oils, which comprises subjecting a body of oil in a still to the action of heated surfaces and thereby heating the oil to a cracking temperature under pressure, withdrawing gases and vapors from the still, and introducing gases and vapors withdrawn from the still at substantially the still temperature in upwardly directed jets, acting on the "air-lift" principle, in an 80 upwardly directed passage within the body of oil, thereby effectively circulating the oil 85 with respect to the heated surfaces.

3. An apparatus for cracking oils, comprising a still provided with heating means 90 for heating the oil therein to a cracking temperature under pressure, means for withdrawing gases from the still, and means for reintroducing a gaseous current or currents comprising a portion of the same into the 95 still in upwardly directed jets, acting on the "air-lift" principle, near the lower end of an upwardly directed circulation pipe arranged in the still and adapted for coacting with the gaseous current or currents for effecting circulation of the oil over the heating surfaces of the still.

4. An apparatus for cracking oils, comprising a still provided with heating means for heating the oil therein to cracking temperature under pressure, means for withdrawing gases and vapors from the still, and means for reintroducing, at substantially the still temperature, a current or currents comprising a portion of the withdrawn gases and 105 vapors into the still in upwardly directed jets near the lower end of an upwardly directed circulation pipe therein adapted for co-acting with the gaseous current or currents and for effecting circulation of the oil 110 with respect to the heating surfaces by the "air-lift" principle.

In testimony whereof we affix our signatures.

WARREN F. FARAGHER.
WILLIAM ARTHUR GRUSE.
